UNITED STATES PATENT OFFICE.

GUSTAV BEHM, OF CHICAGO, ILLINOIS.

DESIGN FOR A WOODEN-CHAIR SEAT.

No. 38,712.

Specification for Design.

Patented July 30, 1907.

Application filed September 17, 1906. Serial No. 385,044. Term of patent 14 years.

To all whom it may concern:

Be it known that I, GUSTAV BEHM, a citizen of the United States, residing at Chicago, in the county of Cook and State of Illinois, have invented a new, original, and ornamental Design for Wooden-Chair Seats, of which the following is a specification, reference being had to the accompanying drawing, forming part thereof.

Figure 1 is a perspective view of a wooden

chair seat showing my new design. Fig. 2 is an elevation of same.

I claim:—

The ornamental design for a wooden chair seat as shown.

GUSTAV BEHM.
